UNITED STATES PATENT OFFICE.

JAY L. HARRISON, OF LEBANON, INDIANA.

WAGON-BRAKE.

SPECIFICATION forming part of Letters Patent No. 276,686, dated May 1, 1883.

Application filed September 18, 1882. (Model.)

To all whom it may concern:

Be it known that I, JAY L. HARRISON, of Lebanon, in the county of Boone and State of Indiana, have invented certain new and useful Improvements in Wagon-Brakes; and I do hereby declare that the following is a full, clear, and exact description of the invention, which will enable others skilled in the art to which it appertains to make and use the same, reference being had to the accompanying drawings, which form a part of this specification.

This invention relates to wagon-brakes, and appertains especially to that class of brakes that will lock the wagon while going downhill, and has for its object to provide simple, durable, inexpensive, and efficient mechanism for readily effecting this end without interfering with any backward movement of the vehicle.

In the drawings, Figure 1 is a perspective view of the running-gear of a wagon, the body being removed. Fig. 2 is a vertical longitudinal sectional view. Fig. 3 is a cross-section in detail on the line *x x*, Fig. 2. Fig. 4 is a detail perspective view of the hinged brake, and Fig. 5 is a sectional detail view of the latter.

Referring to the drawings, A designates the front axle-tree; B, the axle, and C C the wheels. On axle-tree B are arranged the hounds D D, carrying the reach-plate E and front bolster, F. G is the rear axle-tree; H, the axle, and I I the wheels. On axle-tree G are arranged the rear hounds, J J, which support the rear bolster, K. L is the reach, extending forward to the king-bolt M.

The front ends of front hounds, D D, are provided on their under side with a plate, N, which supports the sliding tongue O, the latter moving between the ends of the hounds, and with its rear end in a groove, P, in the under edge of a cross-brace, Q, on the hounds. Tongue O is provided with a plate, R, through which passes the vertical pin S, that secures the double-tree T. To the top of pin S is pivoted a rearwardly-extending connecting-rod, U, pivoted at its rear end to a lever, V, having its fulcrum-bearings in a bracket, W, on the reach. This pivotal connection of rod U is preferably accomplished by passing its end through a loop, X, at the top end of lever V and pivoting it to a swivel-bolt, Y, working in loop X.

Through a perforation, Z, in the lower end of lever V, passes a V-shaped connecting-rod, A', having its ends B' B' pivoted to the inner ends of the levers C' C', arranged on a cross-board, D', supported by the rear hounds, J J. 55 Spring-braces E' extend from the pivot of levers C' rearwardly to the axle-tree G.

On the outer ends of levers C' C' are arranged the brakes F'. These latter comprise a securing-strap, G', having an eye, H', at its top, in which works a top link, I', with its other end in an eye, J', at the top of a shoe-plate, K'. Plate K' has side flanges, L' L', between which is secured the brake-shoe M'. By this hinged arrangement of the brakes they 65 offer resistance to only the forward movement of the wheels, and will not interfere with their backward movement. When not desired for use the brakes may be thrown over, as shown in dotted lines.

In lieu of the connecting-rod U, a horizontal bar, N', may extend from the tongue. The rear end of this bar is bifurcated, and the arms O' O', thus formed, pass through openings P' in the front bolster. The rock-shaft Q' at the 75 rear of arms O' O' is then connected to lever V by a suitable rod. (Not shown.)

The operation and advantages of my invention will be readily understood. In going downhill the back-pressure of the horses causes the 80 tongue to slide back, which operates rod U to throw lever V over, causing the said lever to draw the inner ends of the levers C' C' forward, while its outer ends clamp the brakes against the wheels. The brakes act on the 85 wheels only when they are moving forward. In simply backing the wagon the brakes will of course be clamped against the wheels in the manner above described; but the brakes, by being hinged as shown, offer no resistance to 90 the backward movement of the wheels.

I claim as new—

The combination of the front hounds having a cross-brace provided with the groove in the underside, the tongue sliding in said groove 95 and provided with the top strap, under which is pivoted the double-tree by a pin or bolt, the connecting-rod secured to said double-tree pin and extending rearwardly, the vertical lever pivoted in brackets at the front of the rear 100

hounds, the V-shaped connecting-rod, having its vertex or center passing through a perforation in the lower end of the vertical lever, the brake-levers, and the brake-plates hinged on the said levers and carrying the detachable brake-shoes, as set forth.

In testimony that I claim the foregoing as

my own I have hereto affixed my signature in presence of two witnesses.

JAY L. HARRISON.
